UNITED STATES PATENT OFFICE.

AUGUST FIESSLER, OF STUTTGART, GERMANY.

UTERINE APPLICATOR.

1,129,657.

Specification of Letters Patent. Patented Feb. 23, 1915.

Application filed June 6, 1914. Serial No. 843,419.

To all whom it may concern:

Be it known that I, AUGUST FIESSLER, gynecologist, a citizen of the German Empire, and residing at Stuttgart, Germany, have invented certain new and useful Improvements in or Relating to Uterine Applicators, of which the following is a specification.

The subject-matter of my invention is a 10 uterine applicator *i. e.* a device to be introduced into the channel of the cervix uteri for enabling medicaments to act continuously on the mucous membrane of the cervix uteri and on the secretions therefrom.

15 The novel feature of a device according to the invention is the combination of a preferably projectile-shaped body containing the medicaments to be employed with an elastic or yielding carrier which does not fill

20 the channel of the cervix uteri and which anchors itself in the position of use in the wall of the cervix. In a preferred form of the device according to the invention the body containing the medicaments is carried

25 by an elastic bow of fine steel or silver wire which can yield to any contractions of the uterus, but its spread is limited, and the lower ends of its limbs are provided with laterally projecting short points. When the

30 device is introduced into the cervix uteri these lateral points of the elastic wire bow readily enter into the mucous membrane and hold the device securely in its position of use. The spread of the limbs of the elastic wire

35 bow is limited by a small chain about 6-8 mm. long carried between the lower ends of the limbs of the bow formed as eyes. The bow and its attaching device for the body containing the medicaments and the small

40 chain connecting the limbs of the bow are preferably heavily gold plated, so that the carrier of the body containing the medicaments remains absolutely sterile and does not rust or corrode even when left in the

45 patient for a long time.

A device according to my invention is introduced into the uterus by means of a novel tubular instrument in such manner that the point of the body containing the medicaments does not quite reach the inner mouth of the uterus, while its lowest point is located a few millimeters above the outer mouth of the uterus. The herein-described device is thus placed only in the middle part 55 of the channel of the cervix uteri, so that it establishes no connection between the chan-

nel of the cervix uteri and the vagina which might lead to infection of the uterus. A device according to my invention is removed from the cervix uteri by means of a 60 novel, likewise tubular instrument in such manner that the lateral points of the device are removed from the wall of the cervix without causing injury thereto.

In contradistinction to known devices for 65 introducing medicaments into the uterus the herein-described device is of such a construction, that it cannot cause any complaints due to pressure, nor can it cause painful contractions of the uterus, and it does not 70 check the discharge of the secretions of the uterus, but assure the same taking place normally. The medicinal body of the device requires to be of only a small size without any danger of its being forced out of the 75 uterus after a short time, as is the case with known devices. The composition of the medicinal body will depend on the effect desired in each case. It may be such that the medicinal body is non-poisonous and is 80 not caustic, but is nevertheless bactericidal and insures a good remedial action, particularly in chronic cervical gonorrhea.

Good results are obtained with a medicinal body of the following composition:— 85 itrol=silver citrate (about 75%), aristol=di-iodin-dithymol (about 15%), lygosin-quinin=quinin + diorthooxybenzol-acetone (about 10%). Another suitable composition of the medicinal body is the following:— 90 nosophen=tetra-iodin-phenolphthalein (about 15%), loretin=meta-iodin-orthooxychinolanasulfo-acid (about 30%), aristol=di-iodin-dithymol (about 30%), boric-acid (about 25%). When the medicinal body has such a composition the action of the same is not exhausted even after 95 the device has been in use for several weeks.

One form of a device according to my invention and forms of instruments for introducing and removing the same is represented by way of example in the accompanying drawing wherein:

Figure 1 shows the device in its position of use in the cervix uteri; Fig. 2 is a front-elevation of the device on a scale larger than full size, and Fig. 3 is an end elevation of the same; Figs. 4 to 7 show the introducing instrument, Fig. 4 being a side elevation, partly in section, Fig. 4^a a top plan view, 105 Figs. 5 and 6 front and side elevation respectively, of the upper end of the intro-

ducing instrument with the device inserted therein, and Fig. 7 an elevation corresponding to Fig. 5 showing the instrument open. Figs. 8 to 10 show the removing instrument 5 in section in three different positions.

Referring firstly to Figs. 1 to 3, the device for enabling solid medicaments to act continuously on the mucous membrane of the cervix uteri comprises the projectile-shaped 10 solid, consisting of or containing a medicinal body *a* soluble with difficulty of about 5-6 mm. outside diameter and 7-8 mm. long, the attachment device *b* for the same and the elastic wire bow or carrier *c* carrying the 15 attachment device. The lower ends of the limbs of the wire bow *c* are bent into small eyes or loops *d* which in the example illustrated are located at right angles to the plane of the bow *c*. These loops *d* terminate 20 in points *e* about 2 mm. long which are directed at right angles to the eyes and project laterally outward. The two loops *d* are connected by a well soldered chain *f* about 6-8 mm. long, so that when the bow 25 is spread out the distance between the extreme ends of the two points *e* does not exceed about 10-12 mm. When the bow is spread out in its position of use its height is about 8 mm., so that the total height of 30 the device is about 15-16 mm.

The illustrated device is used by its being inserted in the manner described hereinafter by means of the instrument represented in Figs. 4 to 7 into the cervix uteri *g* so that 35 the medicinal body *a* is directed toward the inner mouth *h* of the uterus, *i. e.*, upward, but does not contact with this mouth. The points *e* of the bow *c* are then located about 4-5 mm. above the outer mouth *i* of the 40 uterus and, as shown in Fig. 1, enter in this position into the mucous membrane of the cervix uteri, so that the entire device is fixed perfectly securely, but can yield to any contractions of the uterus.

45 The instrument represented in Figs. 4 to 7 for introducing a device according to Figs. 2 and 3 into the cervix uteri substantially comprises a tube *k* about 6 mm. wide and 25 cms. long provided with a handle *l* its 50 upper end being bent at an obtuse angle for the purpose of more readily introducing the instrument into the cervix uteri. A plunger *n* provided with a handle *m* is displaceable in the tube *k*. The upper end of 55 the tube is divided in the middle, and the one part *o* of this end is arranged to fold as shown in Fig. 7, it being connected by a hinge to a ring *p* inserted in the tube *k*. The portion *o* of the tube can be held in its 60 closed position (Figs. 4 to 7) by a ring *q* which surrounds the tube *k* and is displaceable on the tube between two stops *r* and *s* on the tube and in its upper position, in which it bears against the stop *r* holds the 65 two halves together. The upper stop *r*

serves at the same time for marking the place up to which the instrument carrying the device to be inserted into the channel of the cervix uteri must be introduced into the latter from the outer mouth of the uterus. Each of the two halves of the upper end of the tube is provided in a plane at right angles to the plane of division with a slot *t* about 6 mm. long which runs longitudinally of the instrument and enlarges 70 downwardly. This instrument is used as follows:—The device according to Figs. 2 and 3 is inserted into the instrument when the part *o* is turned downward, and after this part *o* has been turned upward the device *a*, *b*, *c* is held by the instrument in the manner which will be readily understood from Figs. 5 and 6. The points *e* of the device are located about 2 mm. below the ends of the slots *t* and are firmly clamped 75 inside the instrument, so that when the instrument is inserted into the channel of the cervix uteri the walls of the latter cannot be scratched by the points. When the upper end of the instrument has been inserted 80 into the cervix uteri and the plunger *n* which was originally in the position shown in Fig. 4 is pressed upward in the tube *k* by means of the handle *m*, the upper end 85 of the plunger then abuts against the chain *f* and the device *a*, *b*, *c* is lifted so far that the points *e* are released, whereupon these move outward through the slots *t* and enter 90 into the mucous membrane of the cervix uteri and thus fix the device in the latter. 95 The empty instrument can then be withdrawn downward from the uterus and the vagina.

The instrument shown in Figs. 8 to 10 is 100 used for removing the device *a*, *b*, *c* from the cervix uteri. This instrument likewise comprises a tube *u* about 6 mm. wide and 25 cms. long provided with a handle *v* and its upper end is likewise bent at an obtuse angle. 105 Inside the tube is a piston-like displaceable 110 device or plunger *w* passing through a long slot in the tube and which is provided with a handle *x*. On the upper end of the device *w* is a rod *z* having a small hook *y* whose point is turned toward the rod *z* in order 115 to render impossible all injury of the wall of the cervix when the instrument is being introduced into the same, which is done when the hook is pushed out of the tube.

The removing instrument is used as follows:—The upper end of the instrument with the hook *y* projecting about 1 cm. out of the tube *u* is inserted into the cervix uteri and the chain *f* is caught by the hook (Fig. 8). The tube *u* is then pushed upward until its upper end bears against the device *a*, *b*, *c* to be removed, as shown in Fig. 9. The device *w* and the hook *y* are 125 then retracted until the hook is located about 1 cm. below the upper end of the tube 130

u. The hook pulls the device a, b, c, downward with it and draws it into the tube u of the instrument (Fig. 10). The points e are hereby removed from the cervix uteri 5 without injuring the same and the device a, b, c can then be removed downward with the instrument in the position shown in Fig. 10 out of the uterus.

What I claim and desire to secure by Letters Patent of the United States is:—

1. In a uterine applicator the combination with a body containing the medicaments to be employed; of an elastic carrier arranged to carry said body and to detachably anchor itself in its position of use in the wall of the cervix, a free passage being left in the channel of the cervix uteri, when the carrier is fixed therein. 15
2. In a uterine applicator the combination with a projectile shaped body for containing the medicaments to be employed; of an elastic carrier arranged to carry said body and to detachably anchor itself in the position of use in the wall of the cervix, a 25 free passage being left in the channel of the cervix uteri, when the carrier is fixed therein.

3. In a uterine applicator the combination with a body containing the medicaments to be employed; of an elastic carrier having lateral outwardly directed points arranged to enter into the mucous membrane of the cervix uteri to hold the said carrier securely in its position of use, a free passage being left in the channel of the cervix uteri, when the carrier is fixed therein. 30

4. In a uterine applicator, the combination with a body containing the medicaments to be employed; of a yielding carrier 40 adapted to carry said body and arranged to detachably anchor itself in the position of use in the wall of the cervix, a free passage being left in the channel of the cervix uteri when the carrier is fixed therein, and means 45 for limiting the maximum width of said carrier.

5. In a uterine applicator, the combination with a body containing the medicaments to be employed; of a yielding carrier 50 having lateral outwardly directed points arranged to enter into the mucous membrane of the cervix uteri and to hold said carrier securely in its position of use, a free passage being left in the channel of the cervix uteri 55 when the carrier is fixed therein, and means for limiting the maximum distance between the ends of said points.

6. In a uterine applicator the combination with a body containing the medicaments to be employed; of an elastic carrier 60 adapted to carry said body and arranged to detachably anchor itself in the position of use in the wall of the cervix, a

free passage being left in the channel of the cervix uteri, when the carrier is fixed 65 therein, and a chain attached by its ends to the carrier for limiting the maximum width thereof.

7. In a uterine applicator the combination with a body containing the medicaments to 70 be employed; of an elastic carrier consisting of a bow of wire having lateral outwardly directed points arranged to enter into the mucous membrane of the cervix uteri and to hold said carrier securely in its position of use, a free passage being left in the channel of the cervix uteri, when the carrier is fixed 75 therein.

8. In a uterine applicator the combination with a body containing the medicaments to 80 be employed; of an elastic carrier consisting of a bow of fine wire having lateral outwardly directed points arranged to enter into the mucous membrane of the cervix uteri and to hold said carrier securely in its 85 position of use, a free passage being left in the channel of the cervix uteri, when the carrier is fixed therein, and means for limiting the maximum distance between the ends of said points. 90

9. In a uterine applicator, the combination with a body containing the medicaments to be employed; of an elastic carrier consisting of a bow of fine wire having lateral outwardly directed points arranged to 95 enter into the mucous membrane of the cervix uteri and to hold said carrier securely in its position of use, a free passage being left in the channel of the cervix uteri, when the carrier is fixed therein, the portions 100 of the bow adjacent to the points being formed as loops, and a chain having its ends attached to said loops.

10. A uterine applicator, comprising in combination an elastic bow having lateral 105 outwardly directed points at the ends of the limbs thereof, a chain connected to the ends of the limbs and an attachment device carried by the bow for carrying a medicinal body for treating the mucous membrane. 110

11. A uterine applicator, comprising in combination an elastic bow having lateral outwardly directed points at the ends of the limbs thereof, a chain connected to the ends of the limbs, an attachment device carried 115 by the bow and a medicinal body for treating the mucous membrane of the cervix uteri normally carried by the attachment device.

In testimony whereof, I affix my signature in the presence of two witnesses.

AUGUST FIESSLER.
